DESIGN FOR A BOOTH

John M. Miller, Bend, Oreg.

Application May 11, 1936, Serial No. 62,603

Term of patent 7 years

To all whom it may concern:

Be it known that I, John M. Miller, a citizen of the United States and a resident of the city of Bend, county of Deschutes, State of Oregon, have invented a new, original, and ornamental Design for a Booth, of which the following is a specification, reference being had to the accompanying drawing, forming part thereof.

I claim:

The ornamental design for a booth substantially as shown.

JOHN M. MILLER.
